MOP HEAD UNIT

Hugh Murphy, Hockering, Woking, Surrey, England,
assignor to The Prestige Group Limited, London, England, a company of Great Britain

Filed Apr. 20, 1962, Ser. No. 69,784

Claims priority, application Great Britain Nov. 23, 1961

Term of patent 14 years

(Cl. D9—2)

FIG. 1

FIG. 2

FIG. 1 is a top perspective view of a mop head unit showing my new design.

FIG. 2 is a bottom perspective view thereof.

FIG. 3 is an end view showing the mop head unit as it appears from the left hand side of FIG. 1.

FIG. 4 is a section taken along line 4—4 of FIG. 1.

I claim:

The ornamental design for a mop head unit, as shown.
